UNITED STATES PATENT OFFICE.

ALONZO E. YOUNG, OF BOSTON, MASSACHUSETTS, ASSIGNOR TO FRANCIS L. KING, OF SAME PLACE.

DESIGN FOR GLASS HEAD FOR DOOR-KNOBS.

Specification forming part of Design No. 5,963, dated June 25, 1872.

Specification describing a Design for a Glass Head for Door-Knobs, Bell-Pulls, &c., invented by ALONZO E. YOUNG, of the city of Boston, county of Suffolk and State of Massachusetts.

The nature of my design consists in an improved form for that part of door-knobs, bell-pulls, &c., which may be properly designated as the head, and is fully represented in the accompanying photographic illustration, to which reference is herein made.

A represents a perspective view of the back part of my improved design for a head or knob for door-knobs, bell-pulls, &c., showing the central projection D. B represents a perspective view of a similar head lying upon its face, showing the sides and back. C represents a perspective view of the face of a head of similar form and appearance. It will be observed that the face is plain and smooth. The back is also plain, with the exception of the projection D. The front face and back are parallel

with each other, the thickness between being about five-eighths or three-fourths of an inch. The sides are in a circular form. The projection D, in the central part of the back of the head, is about one-fourth of an inch in length and one inch in diameter. The sides are circular, and the groove E extends completely around the periphery of the projection. The end of the projection may be ornamented, as shown. When transparent glass is used the figure is plainly shown through the face. The projection, *per se*, forms no part of this design application.

What I claim as my invention is—
A design for a head or knob for door-knobs, bell-pulls, &c., made substantially in the form above described.

Boston, Massachusetts, April 26, 1872.
ALONZO E. YOUNG.
